KNEELING BENCH

John E. Shea, Jr., Dorchester, Mass.

Application November 2, 1939, Serial No. 302,468

8 Claims. (Cl. 155—166)

This invention relates to kneeling benches and particularly to devices of this character which are used at funeral wakes observed by members of the Roman Catholic church.

This particular invention is for a knock-down kneeling bench including a kneeling member detachably connected to that portion of the kneeling bench which forms a support for the arms of any person properly positioned on the kneeling member.

The object of the invention is to provide a device of this character which will be rigid and at the same time ornamental and when knocked down will occupy but very little space while being transported to and from the place where it is to be used.

Another object is in making the arm rest in part of two end members each having a plurality of vertical spaced tubes, the upper ends of the tubes in each end member being bent inwardly towards the upper ends of the tubes in the other member and alined therewith.

A further object is in providing a demountable section between the alined upper portions of said tubes, said section being formed of spaced tubular members which by slip joints are connected at their opposite ends to the upper ends of the tubes of said end members, a locking device being provided at each end of the demountable section to prevent separation thereof from said end members.

The invention further consists in providing the central section of the arm rest with a detachable holy water font having associated therewith a Sacred Heart illuminated by an electric lamp.

The invention further consists in providing a kneeling member made in two parts and provided at opposite ends with transversely disposed tubular members to receive forwardly extending rods secured to the end members of the arm rest, said rods being locked to said tubular members thereby retaining the kneeling member and arm rest in proper relation to each other.

The invention further consists in providing said kneeling member intermediate the ends thereof with hinged supports.

The invention further consists in providing means for securing the tubes of said end members and the tubular members of the intermediate section spaced apart in parallelism and riveted together with annular spacers between the various tubes and tubular members.

The above objects are attained by the mechanism illustrated in the accompanying drawing.

For the purpose of illustrating the invention, one preferred form thereof is illustrated in the drawing, this form having been found to give satisfactory and reliable results, although it is to be understood that the various instrumentalities of which the invention consists can be variously

arranged and organized, and the invention is not limited to the precise arrangement and organization of these instrumentalities as herein shown and described except as required by the scope of the appended claims.

Of the drawing

Figure 1 represents a front elevation of a kneeling bench embodying the principles of the present invention.

10 Figure 2 represents a vertical section of the same on line 2, 2, on Fig. 1.

Figure 3 represents a section on line 3, 3 on Fig. 2.

15 Figure 4 represents a section on line 4, 4 on Fig. 2.

Figure 5 represents a section on line 5, 5 on Fig. 1, and

Figure 6 represents a section on line 6, 6 on Fig. 1.

20 Similar characters indicate like parts throughout the several figures of the drawing.

In the drawing, 10, 10 are a plurality of vertical tubes having their upper ends curved horizontally as at 11.

25 These tubes 10, 10 are spaced apart and secured together near the top thereof by a long rod 12 riveted to the outer tubes and having annular spacers 13 between said tubes, thus forming two rigid end members 14.

The lower ends of the outer tubes 10 have rubber thimbles 15 mounted thereon to prevent injury to the floor or the covering thereof on which the kneeling bench is to be disposed.

Near the lower ends of the tubes 10 of each end member 14 is brazed or otherwise secured a transverse tubular member 16.

30 The horizontal ends 11 of the tubes 10 of the two end members 14 are in alinement and have interposed between them a removable section 17 made up of a plurality of tubular members 18 which are secured together by two long rods 19 riveted thereto with spacers 20 between the various tubular members 18.

35 Each opposite end of the central tubular member 18 of the section 17 has fixedly secured therein a cylindrical member 21 which has a long outward extension 21x projecting horizontally therefrom and adapted to be slipped into the interior of the central tube 10 of one of the end members 14, thereby forming a slip joint.

40 This extension 21x has a depression 22 therein which is adapted to receive a projection 22x secured to a spring plate 23 secured to the under side of each end of the central tubular member 18 of the section 17.

45 When this projection 22x is disposed in the recess 22 of the extension 21x, the central section 17 is locked to both end members 14.

50 The central section 17 when secured to the end members 14 is inclined upwardly toward the rear

thereof so as to afford a good arm rest for any person occupying the kneeling member 24.

This kneeling member 24 is made in two parts, each part being composed of three tubular members 25 spaced apart and having their outer ends curved downwardly as at 26 with rubber thimbles 15 on the lower ends of a certain portion thereof.

The three tubular members 25 of each part of the kneeling member 24 are secured together near their outer downwardly extending ends by means of two transverse tubular members 27 brazed thereto, each member 27 being adapted to receive a cylindrical projection 28 extending forwardly from the tubular member 26 secured to an end member 14 of the arm rest.

The projection 28 has a depression 29 in its forward end adapted to receive a projection 30 on a spring plate 31 which is secured to the upper side of one of the tubular members 27, thereby locking the kneeling member 24 to the end members 14.

Intermediate the ends of the kneeling member 24 and secured to the inner ends of the tubular members 25 are two metal plates 32 having hinged thereto supports 33.

When these supports 33 are moved downwardly into the position indicated in the drawing, the kneeling member is very rigid and will support considerable weight.

When the kneeling member is not in use the supports 33 will be positioned against the plates 32.

Superimposed upon the tubular members 25 is a board 34 having a cushion 35 on the top thereof.

This board 34 has extending downwardly from its under side spring clips 36 which extend downwardly between the tubular members 25 and retain the board 34 and cushion 35 in proper position on the kneeling member 24.

The abutting ends of one pair of tubular members 25 are provided with a slip joint similar to that shown in Figs. 5 and 6, thereby locking together the two parts of the kneeling member 24.

Detachably mounted upon the central portion of the removable section 17 is a font 36x for holy water and in the rear of this font and connected thereto is a cross 37.

The font 36x has a downward extension 38 in which is mounted a Sacred Heart 39; this Sacred Heart being of crimson glass and illuminated by an electric lamp 39 from which a wire 40 extends to any suitable source of electric supply.

The whole device may be knocked down readily and occupies but very little space when being transported to the place where it is to be used.

Any ornamental design such as a cross 41 may be secured to the outer ends of the end members 14.

When in use my device makes a very rigid construction and owing to its being formed of tubular metal members which are polished and separated from each other, it has a most ornamental appearance when in use.

It is believed that the operation and many advantages of the invention will be understood without further description.

Having thus described my invention I claim:

1. A knock-down kneeling bench having an arm rest comprising end members composed of a plurality of spaced vertical tubes secured to-

gether in parallelism by transversely extending rods and having the upper ends of the tubes of each end member extending towards and aligned with the upper ends of the tubes in the other end member; a removable section composed of parallel tubes interposed between the upper ends of the tubes of said end members and secured thereto by slip joints; and a kneeling member detachably connected to said end members.

2. A knock-down kneeling bench as set forth in claim 1, in which each end member has a transversely disposed tubular member secured thereto and has a forwardly extending rod adapted to be disposed in a tubular member on said kneeling member and locked thereto.

3. A knock-down kneeling bench as set forth in claim 1, in which said kneeling member comprises a plurality of parallel connected tubular members and has a cushion resting thereon and detachably secured thereto.

4. A knock-down kneeling bench having an arm rest comprising end members each composed of a plurality of spaced vertical tubes secured together in parallelism by transversely extending rods and having the upper ends of the tubes of each end member extending horizontally towards and aligned with the upper ends of the tubes in the other end member; means constructed and arranged to connect together the ends of the horizontally disposed portions of said tubes; and a kneeling member detachably connected to said end members.

5. A knock-down kneeling bench having an arm rest comprising end members each composed of a plurality of spaced vertical tubes secured together in parallelism by transversely extending rods and having the upper ends of the tubes of each end member curved inwardly and extending horizontally towards and aligned with the upper ends of the tubes in the other end member; means constructed and arranged to connect together the ends of the horizontally disposed portions of said tubes; and a kneeling member detachably connected to said end members.

6. A knock-down kneeling bench having an arm rest comprising end members each composed of a plurality of spaced vertical tubes secured together in parallelism by transversely extending rods, said tubes of one end member having formed integral therewith horizontally disposed portions extending toward and aligned with similar horizontally disposed portions of the tubes of the other end member; means constructed and arranged to connect together the ends of the horizontally disposed portions of said tubes; and a kneeling member detachably connected to said end members.

7. A knock-down kneeling bench as set forth in claim 1, in which said kneeling member is in two parts, each part composed of a plurality of spaced connected parallel tubes, each part being detachably secured together, and a hinged support secured to the under side of each of said parts.

8. A knock-down kneeling bench having an arm rest comprising end supports and a removable section composed of a plurality of spaced connected parallel tubes interposed between the upper ends of said end supports and secured thereto, and a kneeling member detachably connected to said end supports and composed of a plurality of spaced connected parallel tubes.

JOHN E. SHEA, JR.
